(57) **CLAIM**

The ornamental design for a holder assembly for rolls of paper, as shown and described.

DESCRIPTION

FIG. 1 is a front perspective view of a holder of the holder assembly for rolls of paper, shown isolated from the assembly to show aspects of the design that are not visible when assembled;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a front perspective view of an insert of the holder assembly for rolls of paper, shown isolated from the assembly to show aspects of the design that are not visible when assembled;

FIG. 9 is a front elevation view thereof;

FIG. 10 is a back elevation view thereof;

FIG. 11 is a right side elevation view thereof;

FIG. 12 is a left side elevation view thereof;

FIG. 13 is a top plan view thereof;

FIG. 14 is a bottom plan view thereof;

FIG. 15 is a front perspective, disassembled view of the holder assembly for rolls of paper;

FIG. 16 is a front perspective, assembled view thereof;

FIG. 17 is a front perspective, disassembled view thereof, in use with a roll of paper; and,

FIG. 18 is a front perspective, assembled view thereof, in use with a roll of paper.
